EXPANSIBLE LINK STRAP

Gunter Armbruster, Birkenfeld, Wurttemberg, Germany, assignor to Rodi & Wienenberger Aktiengesellschaft, Pforzheim, Germany, a joint-stock company of Germany

Filed Aug. 6, 1959, Ser. No. 831,968
Claims priority, application Germany Sept. 19, 1958
9 Claims. (Cl. 59—79)

The present invention relates to an expandable link strap for jewelry and general utility purposes, comprising box links placed crosswise of the strap and spring-loaded intermediate links which are withdrawable from the box links and permit expansion or contraction of the strap.

Link straps have already become known which comprise two V-shaped intermediate links placed in opposed symmetrical arrangement and extending through longitudinal slots in the box links from one box link into the next, said links being maintained by helical springs in contact with the ends of said longitudinal slots. When the strap is expanded the box links move apart, the intermediate links emerge from the box links until the helical springs bear against the side walls of the box links, and in virtue of their V-shape they are at the same time squeezed together crosswise of the strap against the resistance of the helical springs. On relaxing the tension of the strap the box links are positively guided along, and pulled together by, the slanting edges of the extending intermediate links because these are pushed apart. It is a disadvantage of this type of strap that its expansibility is limited because the intermediate links cannot be withdrawn from the box links farther than the diameter of the helical springs on both sides permits. Hence when such a link strap is used as a bracelet for a wrist watch the bracelet is difficult to slip on to the wearer's wrist.

It is the object of the present invention to eliminate this disadvantage.

According to the invention the intermediate links consist of two sleeves which are adapted to be telescoped together against spring resistance transversely across the strap, and which, towards the edges of the strap, have open ends into which project retaining extensions from the side walls of the box links for retaining the intermediate links by intercepting the side walls of the sleeves when fully withdrawn from the box links.

In this form of construction of the strap the intermediate links may be withdrawn from the box links to the full extent of their width, thus increasing the expansibility of the strap. Moreover, individual links may be readily removed to shorten the strap or links inserted to make it longer.

Two preferred embodiments of the subject matter of the invention are illustrated in the accompanying drawing in which—

FIG. 1 is a top plan view, partly in section, of a portion of a link strap, partly contracted and partly expanded;

FIG. 2 is a view similar to FIG. 1, but showing a portion of a contracted link strap according to another embodiment;

FIG. 3 is a similar view showing links during shortening or lengthening the strap, and

FIG. 4 is a perspective view of a pair of expanded links.

FIG. 1 shows a link strap which consists of box links A and intermediate links B. In both its longitudinal side walls 1 each box link A has longitudinal slots 2 through each of which extends the respective half of an intermediate link B to the adjacent box link A.

The intermediate links B consist of two sleeves 3 and

2

4. The sleeve 4 has a reduced extension 5 slidably inserted crosswise of the strap into the sleeve 3, so that the sleeves can be pushed together until their edges 3¹ and 4¹ meet. The edges 3² and 4² of the two sleeves 3 and 4, which face the outer edges of the strap, are V-shaped, the V's facing opposite directions and bearing against the ends 2¹ of the longitudinal slots 2 of the box links. In opposite portions of the side walls 6 and 7 of the sleeves 3 and 4 abutments 8 are stamped out and bent inwardly 10 in the form of lugs; between same according to the embodiment illustrated in FIG. 1 a leaf spring 9 is sprung along the side wall so as to force the sleeves 3 and 4 apart and to press their V-shaped edges 3² and 4² against the ends 2¹ of the longitudinal slots 2. From the ends 2¹ retaining extensions 10 project into the open ends 11 of the intermediate links B and limit the withdrawal of the intermediate links B from the box links A by intercepting the lateral walls 6 and 7 of the sleeves 3 and 4. When the link strap is expanded, the intermediate links B are pulled out through the longitudinal slots 2 of the box links against the resistance of the leaf springs 9, the sleeves 3 and 4 on account of the V-shaped configuration of their edges 3² and 4² being telescoped together until the retaining extensions 10 intercept the side walls 6 and 7 of the sleeves 3 and 4. As a result the leaf springs 9 arch and their pressure on the sleeves 3 and 4 causes the sleeves to move apart as soon as the tension on the strap relaxes, the box links being positively guided by the V-shaped edges 3² and 4² and pulling together until they 30 make mutual contact again.

The same effect may likewise be achieved by a compression spring 12, as shown in the embodiment illustrated in FIG. 2, said compression spring bearing inside the sleeves 3 and 4 with each end against an intermediate parting wall 13, said parting wall being formed by stamping out a suitable section from each lateral wall 6 and 7 of the sleeves 3 and 4, and bending the ends inwardly in such manner that each end forms one half of a parting wall.

40 The sleeves 3 and 4 of the intermediate links B in both forms of construction are so contrived that when the strap is fully expanded the inner edges 3¹ and 4¹ will not make contact but still leave space for the sleeves 3 and 4 to be telescoped together by an amount equaling at least the length of the retaining extension 10. When the sleeves 3 and 4 are then fully telescoped together by lateral displacement of a box link A (FIG. 3) until their edges 3¹ and 4¹ meet, then said box link A may be disengaged out of the open end 11 of the intermediate links B by first disengaging one retaining extension 10 and then the other, thus permitting additional links to be added to or removed from the strap.

55 The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description and all changes which come within the meaning and range of equivalency of the claims are therefore intended to be embraced therein.

I claim:

60 1. In an elongated, longitudinally expandable strap, a pair of closed box links including abuttingly engageable side walls having confronting elongated slot portions of uniform width therein, said box links extending transversely of the longitudinal axis of said strap, and an intermediate link extending transversely of the longitudinal axis of said strap, said intermediate link including opposite sides slidably telescoped received in said slots of said box links, said intermediate link comprising transversely slidably telescoped sections each including out-

wardly diverging outer camming edges engaged at opposite ends of the slots in said box link side walls, and spring means normally urging said intermediate link sections apart and biasing said box link side walls into abutting engagement, said intermediate link having a maximum thickness in the direction of the width of said slots which is less than said width, said sections being capable of telescoping to a length substantially equal to the length of said slots, said spring means being wholly within said intermediate link, whereby upon longitudinal separation of said box links said slot ends engage portions of said intermediate link camming edges to cause the intermediate link sections to be telescoped transversely relative to the longitudinal axis of said strap and against the biasing pressure of said spring means, said intermediate link sections and said box links including opposed abutment portions interconnecting said links and limiting maximum longitudinal separation of said box links. 5

2. The structure of claim 1, said intermediate link sections comprising a rectangular cross-section extending 20 lengthwise in the direction of the longitudinal axis of said strap, one intermediate link section having a reduced dimension end portion telescopically received within an adjacent end portion of said other intermediate link section.

3. The structure of claim 2, said spring means comprising leaf spring means in said intermediate link sections and normally biasing said sections apart. 25

4. The structure of claim 2, said spring means comprising a compression spring in said intermediate link sections and normally biasing said sections apart. 30

5. The structure of claim 1, said box link side walls including inwardly directed extensions at said slots received within opposite ends of said intermediate link.

6. The structure of claim 1, said intermediate link including opposed walls disposed within said box links, said opposed walls of said intermediate link including portions thereon abuttingly engaging said spring means.

7. The structure of claim 6, said box link side walls including inwardly directed extensions at said slots received within opposite ends of said intermediate link.

8. The structure of claim 6, the wall portions of said intermediate link including pairs of inwardly extending abutment lugs, said spring means comprising a pair of transversely disposed leaf springs terminally engaged on said abutment lugs and extending transversely between said sections.

9. The structure of claim 6, the wall portions of said intermediate link comprising abutments at opposite ends of said intermediate link, extending longitudinally of said strap, said spring means comprising a compression spring disposed transversely of the longitudinal axis of said strap and terminally engaged on said abutments.
